HORSESHOE-CALK.

1,111,891.

Specification of Letters Patent. Patented Sept. 29, 1914.

Application filed January 17, 1914. Serial No. 812,667.

To all whom it may concern:

Be it known that I, LLOYD L. Fox, a citizen of the United States, residing at Lowell, in the county of Penobscot and State of 5 Maine, have invented certain new and useful Improvements in Horseshoe-Calks, of which the following is a specification.

My invention relates to calks for horseshoes and consists of improvements in the 10 form and structure of the calk.

The object of my improvement is to provide a calk which can be welded to the bottom of the horseshoe with a "butt" weld and also to the sides of the shoe with a 15 "scarf" weld, thus insuring a stronger and more permanent joint and preventing the calk from becoming loosened or being knocked off under the rough usage to which it is subjected.

20 The invention is fully set forth in the following specification, illustrated by the accompanying drawings, in which like reference characters designate like parts.

In the drawings:—Figure 1 is a perspective view of a toe-calk constructed according to my invention; Fig. 2 shows the method of attaching the toe-calk and the heel-calks to the horseshoe; Fig. 3 is a sectional view on the line A—A of Fig. 2, illustrating the manner of joining the calk to the shoe with both a "butt" and a "scarf" weld.

In Fig. 1, I have illustrated my improved form of toe-calk C for the forward or toe-35 portion of the horseshoe S and it will be understood that the two heel-calks H, H shown in Fig. 2 are constructed in the same manner, the only difference being that they are made somewhat shorter. The main portion c 40 of the calk C is preferably wedge-shaped in cross-section, to provide a relatively sharp working edge c'; while the upper, broad, flat face c² is adapted to fit against the under side of the horseshoe S and to be welded thereto with a "butt" weld. Projecting upwardly from the top face c² of the calk is a sharp-pointed prong c³ which is adapted to be driven into the metal of the shoe after the latter has been heated to soften it. The 50 main purpose of the prong c³ is to provide a means for locating the calk in position on the shoe before commencing the welding operation. Extending laterally from the sides of the calk at or near its center

are two relatively thin wings or lugs c⁴, c⁴. 55 The lugs c⁴ are provided as a means for securing the calk to the sides s, s of the shoe S with a "scarf" weld and are adapted to be bent or folded around the shoe as illustrated more particularly in Fig. 3. 60

The method of welding my improved calk to the horseshoe will now be described in detail. The shoe is first heated and the calk applied thereto by driving the cold prong c³ through the hot metal. This serves to 65 fix the calk in its proper position on the shoe and the two can then be handled more easily during the welding process. At the same time, the prong c³ serves to hold the calk in place during the welding so that 70 its relation to the shoe will not be disturbed under the hammering to which it is subjected. After the calk C has been located on the shoe in this manner its face c² is welded to the under side of the shoe S with 75 a "butt" weld, so-called. The lugs c⁴ are now bent up against the opposite sides s, s of the shoe S, as shown in Fig. 3, and welded thereto with what is termed a "scarf" weld. It is this "scarf" weld which serves to 80 stiffen and reinforce the joint between the shoe and the calk and prevent the latter from being knocked off under severe side stresses.

Heretofore it has usually been the practice to weld calks to horseshoes with merely a "butt" weld, that is with simply a surface joint between the under side of the shoe and the upper face of the calk. Such a joint, however, is far from being secure 90 and calks applied in this manner invariably become loosened and detached long before they wear out. With my present improvement, by securing the calk to the opposite sides of the shoe with a "scarf" weld, a 95 double reinforcement is provided and the joint is made much more secure so that it effectually resists the severe lateral strains to which the calk is subjected. In other words, with my improved method of welding the calk to the shoe a much stronger and more permanent joint is effected and I have demonstrated the fact that it is practically impossible to loosen the calk with severe 100 blows directed against its sides. As calks 105 are usually applied to shoes during wintry weather, to prevent the horses from slipping, they necessarily receive very rough

usage from striking against frozen ground, and my improvement which makes for greater durability is therefore of much value and importance.

5 I am aware that it has previously been proposed to form side lugs on horseshoe calks adapted to abut the sides of the shoe. Heretofore, however, such arrangements have been used only in connection with calks 10 designed to be fastened to the shoe with screws, bolts, or by the horseshoe nails, and it is my belief that up to the present time no one has ever conceived the idea of welding the calk to both sides of the shoe. That 15 is to say, I believe it to be entirely novel to provide a calk having a plurality of side lugs adapted to be welded to the shoe to

form a "scarf" weld and it is for this novel feature that I claim protection.

What I claim is:—

20 As a new article of manufacture, a horseshoe calk having a main body portion adapted to be welded to the under side of the shoe with a "butt" weld and a plurality of integral lugs extending laterally from 25 said body of the calk to adapt them to be bent around both sides of the shoe to be welded thereto to form a "scarf" weld.

In testimony whereof I affix my signature in presence of two witnesses.

LLOYD L. FOX.
